LOOSE SHEET HOLDER

Filed Dec. 17, 1921

UNITED STATES PATENT OFFICE

JOSEPH EIFEL, OF CHICAGO, ILLINOIS

LOOSE SHEET HOLDER

Application filed December 17, 1921. Serial No. 523,085.

My present invention relates generally to engaging means and more particularly to an arrangement for engaging and securing one or more sheets in predetermined position.

5. The principal objects and advantages of this invention reside in the provision of an improved loose leaf holder including an improved arrangement of the base in sections which may be rectilinearly moved toward 10 and away from each other and adjusted in various positions for varying the dimensions of the base for accommodating varying numbers of sheets in combination with an improved mounting of the sheet-engaging fingers which are of the sheet-impaling type; 15 the provision of an improved means for mounting sheet-engaging elements whereby the elements may be removed or adjusted either independently of each other or as a 20 group with respect to the base member carrying the same for accommodating sheets having different spacing of perforations.

Another object of this invention resides in the provision of the sheet-engaging elements 25 so that they are frictionally held in positions of group and individual adjustment longitudinally of the binder, so that the carrying means therefor may be removed for bodily removing a group of the prongs or so that 30 said prongs may be susceptible of a relatively fine adjustment longitudinally of the binder so that offsetting of sheets at the ends of the binder for indexing purposes and to accommodate sheets of different spacings as 35 to the openings therein or of different lengths may be accomplished.

In the attainment of these objects and of such other objects as may appear or be pointed out in the following description, I have 40 provided a construction one embodiment of which is illustrated in the drawings, wherein—

Figure 1 is an end elevational view of the inside of loose leaf holder or binder in closed position;

Figure 2 is a view similar to that of Figure 1 showing the binder in open or expanded position;

Figure 3 is an end view taken from a position below Figure 1;

Figure 4 is a sectional view taken on line 4-4 of Figure 2 looking in the direction of the arrows; and

Figure 5 is a view taken on line 5-5 of Figure 2 also looking in the direction of the arrows. 55

As will be seen upon viewing the figures of the drawings, I have illustrated my invention as embodied in a holder or binder for loose sheets or leaves in which I use a plurality of sheet-engaging members arranged in two opposed groups 10 and 11, as clearly shown. These groups 10 and 11 each preferably consists of finger portions or posts 12 of the shape illustrated and each arranged to engage in an opening appropriately positioned in the sheets or leaves to be held thereby; the reason for the use of the two opposed groups 10 and 11, each group made up of a plurality of members is to permit of simultaneous engagement with two sets of sheets and to permit of offsetting of these sets by offsetting the two sheet-holding groups 10 and 11.

As these two groups of members 10 and 11 have been illustrated for convenience as substantially alike in all respects, and as similarly supported, on a two-part base 10^a herein-after described the description of one group and its manner of support will suffice for the other. The group of members 10, comprises a plurality of individual elements, each substantially U-shaped in configuration, one leg

stantly U-shaped in configuration, one leg being formed into the rounded engaging finger or post 12, referred to above, and the other leg 13 being preferably flattened and widened as shown and the two legs being spaced a substantial distance apart all for reasons that will be obvious. The legs 13 of all the members or elements 12, of which five have been shown for purpose of illustration, are received within the carrier member 14 which is preferably made of metal doubled over as shown to provide the two walls 15 and 16 between which the legs 13 are received. The engagement between the walls 15 and 16 and the legs 13 is a frictional one which, while permitting of the movement of each member 12 not only relatively to the carrier member 14 but independently of and relatively to one another, nevertheless tends to keep the mem- 100

bers 12 in desired relative positions. For the purpose of limiting this movement to a direction longitudinally of the member 14 and substantially at a right angle to the direction of the fingers 12, I have provided one of the walls 15 preferably of the member 14, and the legs 13 of the members 12, with the inter-engaging portions 17 and 18 which will tend to prevent a lateral disengagement thereof, while permitting the aforementioned movement.

The members 17 and 18 are provided by upsetting the metal of the members 13 and 14 longitudinally, so that there is in effect, a tongue and groove engagement provided between said members 13 and 14, thus preventing their accidental lateral separation or relative displacement, but permitting relative longitudinal displacement of said members as explained. They may be laterally removed separately in the event that the sheet employed has less perforations in it than there are fingers in the binder.

The doubled-up carrier member 14 is received between the side walls 19 and 20 formed by bending both of the base or support members 21 and 21^a as shown in Figures 3 and 4, to form the channels 22 within which are received the carrier members 14. The walls 19 and 20 of the member 21 are preferably parallel to and in frictional engagement with the walls 15 and 16, respectively, of the carrier member 14, and the wall 19 is longitudinally pressed up as shown at 23 to coat with the portion 17 previously described in the same manner that said portion 17 coacts with the portions 18 of the legs 13. By the construction thus far described, I have provided not only for the ready adjustability, removability, and interchangeability of each of the members 12 with reference to the carrier member 14 independently of one another, but I have also provided for their removability as a unit with the member 14 which, as will be observed, is removable from its position in the channel 22.

As set forth above, I have used the two sets of members 10 and 11 with the fingers 12 of one set extending toward the support for the other set of fingers, each set being carried upon the base members 21 and 21^a in the manner already described and being normally in staggered relationship. For giving these two sets of fingers a relative movement toward and from each other, I have provided the toggle construction comprising the levers 25 and 26 pivoted to each other intermediate their ends in any desired manner such as by the headed member 27, one end of each lever being pivoted at 28, 29 to the base member 21 or 21^a, the other end of each lever having a lost motion connection with the opposite base member by means of the pin and slot connections 30, 31 and 32, 33.

55 A spring 34 passes around the pivot 27, and

has its free ends 35 and 36 in engagement with the pivots 28 and 29, the action of this spring being to force the pivots 28 and 29 apart and thus automatically operate the toggle to extend the base members 21 and 21^a or retract them.

For retaining the toggle in any desired predetermined position, I have provided the lever 25 with the toothed portion 37, coacting with the oppositely facing teeth on the segment 38 carried by the slide 39, the teeth of said segment being maintained in engagement with the toothed portion 37 by the spring 40, having its end 41 in contact with some portion of the structure such as the base member 21, and having its other end in engagement with the upstanding flange 43 on the lower end of the slide 39. Upon viewing the construction of the toothed members 37 and 38 and their association, it will be observed that they prevent any undesired opening of the binder (i. e. separation of the base members 21 and 21^a) beyond the desired position, and that if such further opening is desired, the flange 43 is pushed upwardly and with it the toothed segment 38 upon which the spring 34 will automatically cause a separation of the base members to the fully-extended position of the binder.

It is frequently desired to have the two groups of posts 10 and 11 in a predetermined offset position, as for indexing purposes. For these purposes, I have provided one of the walls such as 16 of one of the members 14, with the bent-down teat 49, which is adapted to engage in any one of the depressions 50 with which the adjacent wall 20 of the base members 21 and 21^a are provided (see Figure 5). This member 14 is further provided with the handle portion 42 for this purpose. With this arrangement the group of engaging fingers 10 can be maintained in any of a number of predetermined positions with reference to the engaging fingers of the other group, three such positions being indicated for purposes of illustration.

It is sometimes desirable that sheets having various entries thereon have their upper or lower margins, as the case may be, offset with respect to each other so as to expose the series of adjacent margins of the sheets to view.

To accomplish this, assuming that the binder is full of sheets, the binder is opened, as shown in Figure 2, and one or a plurality of the sheets which are to be offset are disengaged from the then engaging set of pins, and said sheet or sheets are moved longitudinally of the binder in stepped fashion the distance between two of the opposed pins and again engaged with the pins. Each sheet in succession may be thus held in the binder in offset relation so that, say, the upper edges of each sheet are offset one below the other.

55 If the binder is later employed with other

sheets having perforations located at different points than the sheets originally sold with the binder or originally used in it, then the pins themselves may be adjusted as to their 5 respective spacings by removing the carriers 14 and sliding the pins therein, or by preventing movement of the carrier members 14 and moving the pins relatively thereto. The former is more convenient, as the pins may be 10 measured exactly with the perforations of the sheet more readily by moving a whole group from the binder.

While the material from which the carrier 14 is constructed has been shown relatively 15 heavy, the purpose is to indicate that this will be of slightly stiffer material than channel walls 19 and 20 so that the pins will not readily bend the elements in insertion and removal thereof. The pins may be removed from the 20 member 14 either by sliding them longitudinally therein or by working them back and forth so that their portions 13 will be angularly displaced and thus spread the legs 15 and 16, permitting removal of the pins.

Upon viewing Figure 4, it will be observed 25 that the base members 21 and 21^a include the plate portions 45 and 46 which form the back of the binder and are relatively displaced in position as shown to permit of their telescoping. Secured to each of these portions 45 and 30 46 are the cover members 47, 48 made of any desired or preferred material.

Having thus described my invention and 35 illustrated its use, what I claim as new and desire to secure by Letters Patent is—

1. In a device of the character described, in combination, a base member, a group of sheet-engaging members comprising prongs adapted to impale the sheets, means for supporting 40 said group on said base for displacement longitudinally of the base, and said sheet-engaging members being slidable in said supporting means for individual adjustment relative thereto.

2. In a device of the character described, in combination, a base member, a group of sheet-engaging members comprising prongs adapted to impale the sheets, means for supporting 45 said group on said base for displacement longitudinally of the base, and said sheet-engaging members being slidable in said supporting means for individual adjustment relative thereto, said group of sheet-engaging members being removable upon removal 50 of a portion of the supporting means from the device.

3. In a loose leaf holder, a base member, a supporting member removably mounted on and supported by said base member, and longitudinally adjustable thereon, and a plurality of sheet-engaging elements carried by said supporting member and slidably and relatively adjustable longitudinally and independently thereof.

4. In a loose sheet holder, in combination,

a base member having two parts, sheet-engaging members, means for supporting said sheet-engaging members for adjustment upon and relatively to said parts, but said means limiting such adjustment to directions transversely of the longitudinal axes of said sheet-engaging members, and means for relatively moving said parts of the base member relatively to each other so as to adjust the sheet-engaging members toward and away from each other. 70

5. In a device of the character described, in combination, a base member having a longitudinally extending supporting means substantially U-shaped in cross-section, a plurality of sheet-engaging prongs, a carrier for said prongs extending longitudinally of the base and received in said supporting means, said carrier means being U-shaped in cross-section and said prongs lying transversely of the longitudinal axis of the base and having portions engaging said carrier member, whereby said carrier member and said prongs are frictionally held by said supporting means. 90

6. In a loose leaf holder, in combination, a base member, a plurality of sheet-engaging prongs, a carrier member for said prongs lying longitudinally of said base, said base having means for removably and adjustably receiving said carrier member longitudinally of the base so that said prongs will normally project transversely of the longitudinal axis thereof, and said prongs being individually adjustable in said carrier member along a 100 line parallel to the longitudinal axis of said base.

7. In a loose leaf holder, in combination, a base member, a plurality of sheet-engaging members projecting transversely of the longitudinal axis thereof, a carrier member for said sheet-engaging members extending longitudinally of the loose leaf holder and substantially U-shaped in cross-section to engage adjacent ends of said sheet-engaging members, said base member having a portion thereof bent into U-shaped form in cross-section and extending longitudinally thereof for frictionally retaining said carrier member. 105 110 115

In testimony whereof I have hereunto signed my name.

JOSEPH EIFEL.
